UNITED STATES PATENT OFFICE.

JOHN JOHNSTEN, OF LONDON, ENGLAND, ASSIGNOR OF ONE-HALF TO GLOBE PNEUMATIC ENGINEERING COMPANY, LIMITED, OF LONDON, ENGLAND.

ROTARY COMPRESSOR AND EXHAUSTER.

Application filed September 8, 1920. Serial No. 409,019.

To all whom it may concern:

Be it known that I, JOHN JOHNSTEN, a subject of the King of Great Britain and Ireland, and residing at 1 Victoria Street, 5 London, S. W. 1, England, have invented certain new and useful Improvements in and Relating to Rotary Compressors and Exhausters, of which the following is a specification.

10 This invention relates to rotary compressors and exhausters of the type comprising an inner rotor and an outer casing or member (either rotary or fixed) arranged eccentrically to one another and having a central trifugally held annular liquid piston in the space between the said members.

The object of the invention is to provide an improved form of device of the above character, and the invention consists in a 20 machine of the type referred to comprising a rotor having a plurality of peripheral webs, discs, or plates thereon and with a port through said webs or the like, and a plate or the like, or a plurality of such adjacent to the port for deflecting the gas from one side to the other of the rotor during its rotation so that it enters the machine at one side of the port and after traversing the passages formed by the webs or the like will 30 leave the machine at the other side of the port.

The invention also comprises varying the number of webs, or the like ports and deflecting plates as may be found most suitable for the fulfilment of any given practical requirements.

The accompanying drawings illustrate two forms of rotor or impeller and a complete machine in accordance with the invention.

40 Figure 1 is a front elevation of a left-handed impeller.

Figure 2 is a section on the line A—B of Figure 1, and

45 Figure 3 is a developed plan.

Figure 4 is a similar view to Figure 2, showing a right-handed impeller.

Figure 5 is a transverse sectional elevation showing a complete machine in accordance with the invention.

In carrying my invention into effect in one convenient manner I form my improved machine with the usual outer drum or casting *a'* and an inner rotor *c* arranged eccentrically thereto with an annular liquid pis-

ton within the space between the two members, but the rotor *I* provide with a plurality of upstanding webs or partitions *a* running peripherally round the rotor in order to form a number of passages *b* corresponding to the number of webs or the like adapted, which webs or the like may be formed with or rigidly secured to the rotor *c*.

At two diametrically opposite points of the rotor *I* provide a port *d* which is formed through all the ribs or webs, the depth of the port being substantially equal to or slightly greater than the total displacement of one member relatively to the other due to the eccentric arrangement.

Adjacent to each port *d* I provide one or more plates *e* of a depth substantially equal to the depth of the port, such plate or plates being arranged at an inclination to the peripheral webs or ribs in order to effect lateral displacement of the gas from one side of the machine to the other during the rotation of the rotor.

In the construction shown, for example, I provide the rotor with five ribs and each port with two deflecting plates, one of which extends at an inclination to the peripheral ribs from one side of the port to the middle rib, while the other is arranged parallel to the first and extends from the middle rib to the other side of the port.

It will be understood, however, that these details are given by way of illustration only as I may vary the number of ports (taking care that the communicating passage is never completely unsealed by the liquid piston) and I may also modify the number of ribs or webs and the number and arrangement of deflecting plates to suit any particular requirements that may have to be fulfilled.

Furthermore, I may arrange at one or each side of the rotor a shrouding plate *f* which may be closely adjacent to the rotor or may be distanced apart therefrom in order to form extensions of the ports, which extended chambers are limited by stop members or distance pieces *g* provided for the purpose.

The operation of the device is similar to that of compressors or exhausters of the kind to which the invention refers in that the rotation of the eccentrically arranged rotor causes the latter alternately to dip into and out of the liquid forming the annular liquid piston and by the combined action

due to the rotation and to the eccentricity the air or other medium being operated upon is drawn in through an inlet port at one side of the rotor being guided into certain 5 of the peripheral channels thereon by means of the deflecting plate adjacent to the port and from such channels it is during the further rotation of the rotor guided into the next set of channels by the next succeeding 10 deflecting plate in the other port in the rotor and after traversing such channels finally leaves the rotor through the port at that side remote from the one by which the medium entered.

15 Having now particularly described and ascertained the nature of my said invention and in what manner the same is to be performed, I declare that what I claim is:—

20 1. A rotary compressor or exhauster comprising in combination an outer casing, a rotor arranged eccentrically within said casing, a centrifugally held body of liquid in the space between said members, a plurality of independent webs on said rotor running 25 completely round the circumference thereof and having a port through all said webs and means adjacent to said port for deflecting the gas from one side to the other of the rotor during its rotation, substantially 30 as described.

25 2. A rotary compressor or exhauster comprising in combination an outer casing, a rotor arranged eccentrically within said casing, a centrifugally held body of liquid in the space between said members, a plurality 35 of parallel equally spaced webs on said rotor arranged completely round the circumference thereof and having a port formed through all said webs and means adjacent 40 said port for deflecting the gas from one side to the other of the rotor substantially as described.

30 3. A rotary compressor or exhauster comprising in combination an outer casing, a 45 rotor arranged eccentrically within said casing, a centrifugally held body of liquid in the space between said members, a plural-

ity of independent webs on said rotor arranged completely round the circumference thereof and having a port formed through 50 all said webs and deflecting plates adjacent to said port, substantially as described.

4. A rotary compressor or exhauster comprising in combination an outer casing, a 55 rotor arranged eccentrically within said casing, a centrifugally held body of liquid in the space between said members, a plurality of independent webs on said rotor arranged completely round the circumference thereof and having a port formed through 60 all said webs and deflecting plates adjacent to said port of a depth sufficient to give a seal in the liquid but of less depth than the said webs, substantially as described.

5. A rotary compressor or exhauster comprising in combination an outer casing, a 65 rotor arranged eccentrically within said casing, a centrifugally held body of liquid in the space between said members, a plurality of independent webs arranged completely 70 round the circumference on said rotor and having a port formed through all said webs, means adjacent to said port for deflecting the gas from one side to the other of the rotor and a shrouding plate at one side of 75 said rotor, substantially as described.

6. A rotary compressor or exhauster comprising in combination an outer casing, a 80 rotor arranged eccentrically within said casing, a centrifugally held body of liquid in the space between said members, a plurality of independent webs arranged completely 85 round the circumference on said rotor and having a port formed through all said webs, means adjacent to said port for deflecting the gas from one side to the other of the rotor and a shrouding plate spaced apart from the rotor to form an extension of the adjacent port and stop members for limiting such extensions substantially as de- 90 scribed.

In testimony whereof I have signed my name to this specification.

JOHN JOHNSTEN.
